US00D847933S

(12) **United States Design Patent** (10) Patent No.: **US D847,933 S**
Windfeldt (45) Date of Patent: ** May 7, 2019

(54) **STOCK FOR A GUN**(71) Applicant: **Maxim Defense Industries, LLC**, St. Cloud, MN (US)(72) Inventor: **Michael G. Windfeldt**, St. Augusta, MN (US)(73) Assignee: **Maxim Defense Industries, LLC**, St. Cloud, MN (US)(***) Term: **15 Years**(21) Appl. No.: **29/607,161**(22) Filed: **Jun. 9, 2017**(51) LOC (11) Cl. **22-01**

(52) U.S. Cl.

CLAIM

The ornamental design for a stock for a gun, as shown and described.

DESCRIPTION

FIG. 1 is a perspective view of a first embodiment of a stock for a gun in accordance with my new design, the stock for a gun being in a fully deployed configuration;

FIG. 2 is a front, left, bottom perspective view of the stock for a gun of FIG. 1;
FIG. 3 is a front view of the stock for a gun of FIG. 1;
FIG. 4 is a rear view of the stock for a gun of FIG. 1;
FIG. 5 is a left side view of the stock for a gun of FIG. 1;
FIG. 6 is a right side view of the stock for a gun of FIG. 1;
FIG. 7 is a top view of the stock for a gun of FIG. 1;
FIG. 8 is a bottom view of the stock for a gun of FIG. 1;
FIG. 9 is another perspective view of the first embodiment of a stock for a gun of FIG. 1, the stock for a gun being in a collapsed configuration;
FIG. 10 is a front, left, bottom perspective view of the stock for a gun of FIG. 9;
FIG. 11 is a front view of the stock for a gun of FIG. 9;
FIG. 12 is a rear view of the stock for a gun of FIG. 9;
FIG. 13 is a left side view of the stock for a gun of FIG. 9;
FIG. 14 is a right side view of the stock for a gun of FIG. 9;
FIG. 15 is a top view of the stock for a gun of FIG. 9;
FIG. 16 is a bottom view of the stock for a gun of FIG. 9;
FIG. 17 is a perspective view of a second embodiment of a stock for a gun in accordance with my new design, the stock for a gun being in a fully deployed configuration;
FIG. 18 is a front, left, bottom perspective view of the stock for a gun of FIG. 17;

FIG. 19 is a front view of the stock for a gun of FIG. 17;
FIG. 20 is a rear view of the stock for a gun of FIG. 17;
FIG. 21 is a left side view of the stock for a gun of FIG. 17;
FIG. 22 is a right side view of the stock for a gun of FIG. 17;
FIG. 23 is a top view of the stock for a gun of FIG. 17;
FIG. 24 is a bottom view of the stock for a gun of FIG. 17;
FIG. 25 is another perspective view of the second embodiment of a stock for a gun of FIG. 17, the stock for a gun being in a collapsed configuration;
FIG. 26 is a front, left, bottom perspective view of the stock for a gun of FIG. 25;
FIG. 27 is a front view of the stock for a gun of FIG. 25;
FIG. 28 is a rear view of the stock for a gun of FIG. 25;
FIG. 29 is a left side view of the stock for a gun of FIG. 25;
FIG. 30 is a right side view of the stock for a gun of FIG. 25;
FIG. 31 is a top view of the stock for a gun of FIG. 25; and,
FIG. 32 is a bottom view of the stock for a gun of FIG. 25. The broken lines immediately adjacent the shaded areas represent the bounds of the claimed design. All broken lines are directed to environment and are for illustrative purposes only and form no part of the claimed design.
